UNITED STATES PATENT OFFICE.

TURNER T. POPE, OF HOUSTON, TEXAS, ASSIGNOR OF ONE-HALF TO MARCELLUS E. FOSTER, OF HARRIS COUNTY, TEXAS.

VAPORIZING ATTACHMENT.

1,341,760.

Specification of Letters Patent.

Patented June 1, 1920.

Application filed July 16, 1917, Serial No. 180,853. Renewed April 8, 1920. Serial No. 372,318.

To all whom it may concern:

Be it known that I, TURNER T. POPE, a citizen of the United States, residing at Houston, in the county of Harris and State 5 of Texas, have invented certain new and useful Improvements in Vaporizing Attachments, of which the following is a specification.

This invention relates to new and useful 10 improvements in a vaporizing attachment for printing presses.

The object of the invention is to provide an attachment of the character described by means of which vapor may be applied to 15 the paper as it passes through the press.

In modern printing presses, now in common use, a number of rolls of paper are mounted in the press and the paper is unwound therefrom, in the process of printing, 20 said paper traveling at a very high rate of speed and in case the paper is too dry it is very easily torn and in case the sheet is mutilated at either edge or slightly weakened from any cause, it often tears in two 25 in the process of printing, thus causing delay. Furthermore, the friction caused by the dry sheet of paper passing over the metallic rolls of the press and coming into contact with the other metallic parts thereof 30 at a high rate of speed generates static electricity which tends to cause the paper to adhere to the metal, thus making a considerable pull on the paper necessary in order to move it through the press at the required 35 rate of speed, the resistance sometimes causing the paper to tear in two. If the paper is slightly moistened it is not so liable to tear and the friction of the damp paper does not generate electricity and for that reason the 40 attachment herein described has been provided for the purpose of applying steam to the paper just after it leaves the rolls and before it enters the press.

Furthermore in shipping paper rolls, the 45 ends of the roll sometimes become dented or otherwise mutilated and in unrolling the paper the edges are thereby caused to adhere together, thus causing the paper to tear in two. In order to cause the edges of the plies 50 to separate at the ends of the roll, the device has been arranged to apply steam to said ends which softens the paper and causes the plies to separate so that the paper will readily unwind from the roll without resistance.

A further feature of the invention resides in the provision of an attachment of the character described whereby steam may be applied to the ends of one or any number of rolls, as well as to the paper being unwound from the rolls. 60

In the application of steam to the paper passing through the press, it is essential that steam only be applied, not water in liquid form, as the latter would weaken the paper 65 and cause it to tear. For that reason, I have provided an attachment of the character described whereby all condensed water will be drained out, leaving only the steam in a state of vapor to be applied to the paper. 70

With the above and other objects in view, the invention has particular relation to certain novel features of construction, arrangement of parts and use, an example of which is given in this specification and illustrated 75 in the accompanying drawings, wherein:

Figure 1 is a front elevation of the device as applied to a printing press.

Fig. 2 is an enlarged fragmentary front elevation thereof. 80

Fig. 3 is a side view showing the rolls from which the paper has been partially unwound, and

Fig. 4 is an enlarged fragmentary side elevation thereof. 85

Referring now more particularly to the drawings wherein like numerals of reference designate similar parts in each of the figures, the numerals 1, 1, refer to the side members of the rear end of a printing press 90 wherein a plurality of paper rolls 2 are rotatably mounted, the number of rolls depending upon the character of the press. The paper is unwound from these rolls forming sheets 3, 3, 3, each sheet passing 95 around the respective idler rollers 4 and 5 before entering the press proper. The numeral 6 refers to a steam line which is controlled by the valve 7 and from which leads the two steam pipes 8, 8, arranged on opposite sides of the press and connected by the nozzles 9, 9, 9, said last mentioned nozzles passing under the respective sheets 3 and each of these nozzles has a row of perforations 10 along its upper side through which 100 steam is forced against the corresponding sheet 3 which dampens said sheet, each nozzle 9 is controlled at each end by means of a valve 11 so that steam may enter each of 105 said nozzles from both ends so as to insure 110

an even distribution of steam through said nozzles. At the ends of the rolls are the nozzle pipes 12, 12, 12, which are connected with the nozzles 10 and which lead to and 5 connect with the respective drain pipes 13. Opposite the ends of the rolls these pipes 12 are provided with perforations 14 through which steam is discharged against the ends of the roll and in case any water should 10 connect with the respective drain pipes 13. Dense and collect in the nozzles 9, it will be drained off through the pipes 12 into the drain pipes 13, thus preventing any water in its liquid form from being forced against the paper. The drain pipe 13 is provided 15 with traps 15 between the pipes 12 and the drain pipes converge together into a common pipe 16 provided with the trap 17. These traps prevent any back pressure of steam as only a low pressure of steam is necessary 20 for the operation of this device so that steam may be applied to either one of the rolls or to all of them at the same time if desired. There is only a small amount of water which condenses in the nozzles and 25 drains through the pipes 12 and never enough to fill them up to the perforations 14 so that only steam, and no water, is discharged against the ends of the roll.

The steam is thus applied to the end of each 30 roll from the center to the circumference, moistening the entire end of the roll as it rotates and is also applied to the unwound paper from edge to edge as it passes through the press, thus moistening and toughening 35 the paper, preventing the tearing thereof and also minimizing the generation of static electricity caused by the friction of the paper as it passes through the press.

What I claim is:

40 1. An attachment for printing presses including a steam line, a transverse nozzle connected to said line provided with steam outlets and arranged to project steam against the sheet of paper passing through 45 the press and a nozzle pipe connected to said nozzle provided with steam outlets and arranged to project steam against the end of the roll from which said paper is unwound.

2. An attachment for printing presses 50 including a steam line, a nozzle connected to said line at each end and provided with steam outlets and arranged to project steam against the paper being unwound from a roll, means for controlling the entrance 55 of steam into said nozzle at each end, a nozzle pipe leading from said nozzle and arranged at each end of said roll, said nozzle pipe being provided with steam outlets through which steam is projected against 60 the ends of the roll.

3. An attachment for printing presses in-

cluding a steam line, a pair of steam pipes leading therefrom, a nozzle communicating with each of said pipes, a valve controlling the entrance of steam from each pipe into 65 the nozzle, said nozzle being provided with steam outlets through which steam is projected against the paper being unwound from the roll in the press, a pair of drain pipes and nozzle pipes leading from said 70 nozzle at each end and communicating with the corresponding drain pipes, said nozzle pipes being provided with steam outlets and arranged to project steam through said outlets against the ends of the corresponding 75 paper rolls.

4. An attachment for printing presses including a steam line, a pair of steam pipes leading therefrom, a plurality of nozzles communicating with each of said pipes, a 80 valve controlling the entrance of steam from each pipe into the nozzle, said nozzles being provided with steam outlets through which steam is projected against the paper being unwound from the rolls in the press, a pair 85 of drain pipes and nozzle pipes leading from said nozzles at each end and communicating with the corresponding drain pipes, said nozzle pipes being provided with steam outlets and arranged to project steam through 90 said outlets against the ends of the corresponding paper rolls and traps in said drain pipes between said nozzle pipes.

5. An attachment for printing presses including a steam line, a transverse nozzle 95 connected to said line provided with steam outlets and arranged to project steam against the sheet of paper passing through the press and a nozzle pipe provided with a nozzle arranged to project steam against 100 the end of the roll from which said paper is unwound.

6. An attachment for printing presses including a vapor conduit arranged to project vapor against the sheet of paper passing through the press and means arranged to project vapor against the ends of the roll from which said paper is unwound.

7. An attachment for printing presses including a vapor conduit arranged to project vapor against the sheet of paper passing through the press, and means arranged to project vapor against an edge of the paper while in a roll before being unwound.

In testimony whereof I have signed my 115 name to this specification in the presence of two subscribing witnesses.

TURNER T. POPE.
